United States Patent

Des. 240,082
Patented May 25, 1976

240,082

LAMP

Donald Charles Garwood, Malibu, Calif., assignor to
Merck & Co., Inc., Rahway, N.J.

Filed Sept. 6, 1974, Ser. No. 503,909

Term of patent 14 years

Int. Cl. D23—03; D24—02

U.S. Cl. D83—1 C

Fig. 1.

Fig. 2.

6

Fig. 3.

FIG. 4.

FIG. 5.

FIG. 1 is a front perspective view of a lamp embodying my design;

FIG. 2 is a side view of the lamp of FIG. 1;

FIG. 3 is a front view of the lamp of FIG. 1;

FIG. 4 is a bottom plan view of the lamp of FIG. 1;

FIG. 5 is a rear view of the lamp of FIG. 1; and

FIG. 6 is an end view along line 6-6 of the lamp of FIG. 2.

I claim:

The ornamental design for a lamp, as shown and described.
